UNITED STATES PATENT OFFICE.

WILLIAM MILLS, OF BIRMINGHAM, ENGLAND.

GRENADE AND THE LIKE.

1,223,599.

Specification of Letters Patent. Patented Apr. 24, 1917.

Original application filed June 15, 1915, Serial No. 34,232. Divided and this application filed February 2, 1916. Serial No. 75,654.

To all whom it may concern:

Be it known that I, WILLIAM MILLS, a subject of the Kingdom of Great Britain, residing at Atlas Aluminium Works, Grove 5 street, Birmingham, in the county of Warwick, England, engineer, have invented certain new and useful Improvements in or Relating to Grenades and the like, of which the following is a specification.

10 This invention comprises certain improvements in, or relating, to grenades, and the like, and is applicable to an explosive grenade which can be thrown by hand, or by means of a sling, catapult, gun, or grenade 15 projecting machine, or which can be thrown or dropped from air-ships or aeroplanes.

The type of grenade to which the present invention refers is that in which the grenade comprises or involves a hollow body 20 adapted to contain the explosive charge, within which body a spring-impelled striker is incorporated, which is normally retained in its retracted condition by a lever disposed externally and adapted to be retained 25 in relation thereto normally by retaining means, and, when such means have been released, by the hand grasping the grenade so as to be released in the act of throwing the grenade.

30 In grenades of this type heretofore proposed the external lever has been adapted to rock on the edge of the opening in the grenade body from which the striker projects; this arrangement I have found unsatisfactory in action and the lever is liable to fail to release the striker. My present invention has for its purpose to provide for a free and particularly effective and certain operation of the lever and with this object in view the 35 external member is mounted with a pivot advantageously constituted by trunnions adapted to work in bearings provided upon or in connection with the body of the grenade.

40 In order that this invention may be clearly understood and readily carried into practice, reference may be had to the appended explanatory three sheets of drawings, upon which:—

45 Figure 1 is a sectional elevation of a hand grenade according to the present invention.

Fig. 2 is a perspective view of the grenade shown in Fig. 1.

Fig. 3 illustrates separately in perspective

the external lever of the grenade shown in Figs. 1 and 2.

Fig. 4 illustrates a modified hand grenade according to the present invention.

Fig. 5 illustrates in perspective, separately, the external lever of the grenade shown in Fig. 4.

Fig. 6 is a sectional elevation of a further modification of the present invention.

Fig. 7 illustrates in sectional elevation a still further modified embodiment of the present invention.

In a convenient embodiment of the present invention as shown in the drawings, *a* is the hollow body of the grenade which may be of any suitable shape or form, adapted to contain an explosive charge. Within this body a tubular housing *b* is incorporated, in which a spring-impelled sliding or longitudinal hammer *c* is disposed, adapted to operate upon a cap *d*, which latter is in communication with a time fuse *e* which leads to the detonator *f*, the latter being contained in a second tubular housing *g* and being adapted to fire the explosive contained in the body of the grenade.

The hammer *c* is retained in its retracted position shown in Fig. 1 of the drawings by an external lever *h*, the extremity *i* of which is adapted to engage with the under side of a flange or enlargement *j* provided at or upon the outer extremity or part of the hammer, this lever being extended around the exterior of the body of the grenade, so that it can be retained in relation to the latter by the hand grasping the grenade, the lever being adapted to release the hammer when it is itself released by hand or the throwing appliance in the act of throwing.

One method of retaining the lever in its normal position in relation to the grenade is shown in the drawings, and comprises a split pin *k* adapted to be passed through perforations in the lever, and also through perforations in lugs or projections *l* provided upon or integral with the body at positions one on each side of the lever. It will be noted that the provision for incorporating this pin is conveniently disposed near to the extremity of the lever in the vicinity of the hammer *c*, or in the part or half of the lever associated with such hammer, so that the end *m* of the tail of the lever can be retained by the hand grasping the grenade, a high

standard of leverage being thereby insured during the operation of removing the split pin *k*. The split pin *k* is conveniently composed of metal of a pliable character, so that the sections of the pin may be opened to prevent the possibility of accidental separation of the pin at a time before it is desired to throw the grenade. The two split portions of the projecting part of the pin may, 10 however, be collectively bent, as for instance in a direction toward the body of the grenade, as shown in Fig. 2. A ring may be incorporated to assist removal of the pin.

While I have described with particularity 15 one device for retaining the lever in its normal position, I wish it to be understood that the retaining means may be varied considerably.

The lever *h* may conveniently be of channel form, and the part of the lever at the 20 base of the channel adjacent to the head of the striker with which the lever engages may be formed to a concave or recessed shape so that the base part of the channel lever may engage with the head of the 25 striker around a substantial part of the circumference.

At a position near to the head of the 30 striker the lever is furnished with a fixed pivot *n* so incorporated as to project in the form of trunnions, one on each side of the lever, which trunnions are adapted to work in grooves provided in lugs, ribs, or projections *o* integrally provided upon the external 35 surface of the body.

As shown in the drawings, the lever *h* is 40 of such form and so incorporated in relation to the external surface of the grenade that when the tail of the said lever *h* flies or 45 moves away from the body of the grenade, the extremity of the lever in the vicinity of the enlargement *j* of the striker cannot come into contact with the body of the grenade in a manner which would foul the action of 50 the lever.

The form of grenade which has been described is adapted to be thrown by hand, or 55 by a throwing appliance. In the latter case the throwing appliance is furnished with a 60 ring, socket or the like for the reception of the body of the grenade, and such ring, socket or the like is adapted to receive the tail of the lever *h*, so that the latter is retained in its normal position until, the 65 grenade actually leaves the throwing appliance.

p is a socket which may if desired be 70 suitably furnished in the closure member *q* of the grenade and into which a shaft or 75 handle may, if desired, be screwed, if it should be desired to throw the grenade (together with the shaft or handle).

The socket *p* may be alternatively utilized 80 for the reception of a rod, lug, or projection, 85 adapted to be inserted into the barrel of a

rifle when it is desired to utilize the latter for the purpose of projecting the grenade, or such a rod, lug or projection may be formed integrally with the closure member *q*. A 90 socket or ring such as has been described in connection with the throwing appliance is suitably secured to the barrel of the rifle, and is adapted to engage with the lever and retain it in relation to the body of the grenade when the grenade is assembled in 95 the barrel of the rifle, so that when the grenade is projected from the rifle the lever is automatically released.

In cases in which the grenade is projected by a throwing appliance or by a rifle, it is 100 desirable to assemble the grenade in relation to the ring or socket pertaining to the throwing appliance or rifle before the split pin *k* or other equivalent means for retaining the 105 lever is removed.

In cases in which the grenade is furnished with a shaft or handle by which the grenade may be thrown, the lever may, if desired, be applied to the handle as shown in Figs. 6 and 7. In Fig. 6, the tubular housing *b* 90 for containing the spring-impelled striker *c* is contained within the handle, and other characteristics of the grenade will be understood from the foregoing description, which substantially applies equally to Fig. 95 6. In Fig. 7, the lever *r* is disposed in relation to the handle, but its point of pivotal movement in relation to the latter is near to, or at the end of, the handle adjoining the body of the grenade, instead of near to, or 100 at the end of, the handle remote from such body. The lever *r* upon being released, is adapted to release the striker *c*. The lever *r* may be permanently pivoted to the handle at *s* or it may be furnished with trunnions 105 working in bearings comprised of grooves or slots suitably incorporated in the handle. Other characteristics of the grenade shown in Fig. 7 will be understood from the foregoing description, which substantially applies equally to Fig. 7. In Figs. 6 and 7, the detonator housing is disposed in alignment with the housing for the striker, instead of being disposed to the one side of the housing for the striker in the grenade 115 shown in Fig. 7, if, for instance, the internal dimensions of the hollow body of the grenade did not permit of the housings being disposed in the aligned arrangement.

What I claim as my invention, and desire 120 to secure by Letters Patent is:—

1. A grenade or the like comprising in combination, a body, means carried by said body for firing or exploding the grenade, an externally disposed lever adapted to control 125 said firing means, a pivot for said lever, and means providing a bearing for said pivot, said means permitting the arm of the lever to move so as to release said firing means without the short arm of the lever contact- 130

ing with the part in relation to which the lever is pivoted.

2. A grenade or the like comprising in combination, a body, means carried by said body for firing or exploding the grenade, a lever disposed externally of said body and adapted to control said firing means, a pivot for said lever, and means providing a bearing for said pivot in connection with the body of the grenade, said last mentioned

means permitting said lever to move into a position substantially radial to the body of the grenade without contacting with the body.

In witness whereof I have hereunto set my hand in the presence of two witnesses.

WILLIAM MILLS.
